JAMES B. WAGONER, DECEASED, LATE OF LOS ANGELES, CALIFORNIA, BY ALMA M. WAGONER, SPECIAL ADMINISTRATRIX, OF SAN FRANCISCO, CALIFORNIA.

VAGINAL DYNAMO.

1,195,933.

Specification of Letters Patent. Patented Aug. 22, 1916.

Application filed August 31, 1914. Serial No. 860,108.

To all whom it may concern:

Be it known that JAMES B. WAGONER, deceased, formerly a citizen of the United States residing in the city and county of Los Angeles and State of California, has invented a certain new and useful Improvement in Vaginal Dynamos, of which the following is a specification.

This invention relates to vaginal dynamos wherein electrodes of dissimilar metals generate a mild electrical current; and the objects of the invention are, first, to provide an improved vaginal dynamo of such shape and size as will adapt it for use in the vagina; second, to provide an improved means for producing a beneficial effect in the vagina with no discomfort to the wearer; third, to provide a device of the character described which may be cheaply and easily constructed; fourth, to provide a device of the character described having one end thereof concaved so as to fit snugly against the cervix.

For a full and complete comprehension of the invention reference should be had to the drawings forming a part of the present specification wherein like characters of reference are used to designate similar parts throughout the said specification and drawings and in which—

Figure 1 is a side elevation of the dynamo disclosing the shape thereof and the electrodes thereon. Fig. 2 is a view taken on line X—X of Fig. 3 of the drawings in the direction indicated by the arrow disclosing the connection between the central conductor and one of the electrodes. Fig. 3 is a longitudinal sectional view of the device disclosing the manner in which the electrodes are secured to the dielectric core and the concaved surface on the end electrode whereby the cervix is snugly engaged, also the central conductor and the manner in which it is connected to the electrodes.

In order to provide a device of the character described which will generate a mild electric current, when applied, thereby imparting a beneficial effect with no discomfort to the wearer, a central arcuate core 1 of a dielectric material is provided of such

shape and size as will readily and comfortably fit into the vagina. Upon one end of the core 1 an electrode 2 is screwed while a similar electrode 3, of dissimilar metal, is provided near the other end of the said core 55 1. An inner metal connection 4 is cast within the core 1 and the outer end 5 thereof is engaged by the concaved end 6 of the electrode 2. A suitable metallic connection 7 properly connects the electrode 3 with the 60 central connection 4. The connection 4 is provided with a threaded end 8 upon which is screwed a suitable head 9, by means of which the dynamo may be easily inserted into and withdrawn from the vagina. While 65 the head 9 is shown comparatively small it may be of such size and character as will prevent the dynamo from being inserted too far into the vagina. The electrode 2 is concaved on the outer end thereof so as to provide 70 a proper area of contact with the cervix.

The dynamo is inserted into the vagina with the electrode 2 innermost so as to properly engage and provide a proper area 75 of contact with the cervix. A mild electric current will be generated which will impart a beneficial result to the surrounding parts of the anatomy.

Having thus described the invention, what 80 is claimed as new is—

1. A vaginal dynamo comprising a central arcuate core of dielectric material; and a suitable electrode secured to each end of the core, one of the said electrodes having a 85 concaved end.

2. A vaginal dynamo comprising a cylindrical arcuate core of dielectric material; electrodes of dissimilar metal secured to the ends of the core, one of the said electrodes 90 having a concaved outer end; and a suitable connection between the electrodes.

3. A vaginal dynamo comprising a cylindrical arcuate core of dielectric material; electrodes of dissimilar metal secured to the 95 ends of the core, one of the said electrodes having a concaved outer end; a suitable connection between the electrodes; and a suitable head secured to one end of the core.

4. A vaginal dynamo comprising a cy- 100

lindrical arcuate core of dielectric material; electrodes of dissimilar metals secured to the ends of the core, one of said electrodes having a concaved end; an inner metallic connection within the core and connected to the electrodes; and a suitable head secured to one end of the core.

In witness whereof, I have hereunto set

my signature in the presence of two subscribing witnesses.

ALMA M. WAGONER,
Administratrix of the estate of James B.
Wagoner, deceased.
